UNITED STATES PATENT OFFICE

92,126

DESIGN FOR AN ELECTRIC LAMP

Richard W. Fisher and Thomas McCarthy,
Beverly, Mass.

Application January 20, 1933, Serial No. 46,909

Term of patent 14 years

To all whom it may concern:

Be it known that we, RICHARD W. FISHER and THOMAS McCARTHY, both citizens of the United States, and residents of Beverly, in the county of Essex, State of Massachusetts, have invented a new, original, and ornamental Design for Electric Lamps, of which the following is a specification, reference being had to the accompanying drawing, forming a part thereof.

The figure of the drawing is a perspective view of an electric lamp showing a base simulating a horseshoe having calks and with the heads of

horseshoe nails exposed, a standard rising therefrom supporting a cylindrical socket for an electric lamp, and a pull for the switch of said socket simulating a horseshoe nail.

We claim:

The ornamental design for an electric lamp as shown and described.

In testimony whereof we have signed our names to this specification.

RICHARD W. FISHER.
THOMAS McCARTHY.
